UNITED STATES PATENT OFFICE

GEORGE B. McBEAN, OF CHICAGO, ILLINOIS, ASSIGNOR TO MECHANICAL & ELECTRICAL MANUFACTURING COMPANY, OF CHICAGO, ILLINOIS, A CORPORATION OF ILLINOIS.

SOCKET FOR INCANDESCENT ELECTRIC LAMPS.

No. 903,141.

Specification of Letters Patent.

Patented Nov. 3, 1908.

Application filed May 18, 1907. Serial No. 374,433.

To all whom it may concern:

Be it known that I, GEORGE B. McBEAN, a citizen of the United States, and a resident of Chicago, Cook county, Illinois, have invented certain new and useful Improvements in Sockets for Incandescent Electric Lamps, of which the following is a specification.

This invention relates to sockets for incandescent electric lamps, and relates particularly to the type of socket known to the trade as "weatherproof" sockets, which are especially designed and adapted for outdoor use and in which the electrical connections are sealed up by means of nonconducting, waterproof cement or wax to prevent access thereto of moisture which would be liable to cause leakage or short circuiting. Certain features of my improvements, however, admit of general application to "open" as well as to "weatherproof" sockets.

Heretofore, so far as I am aware, the universal practice has been to attach the shells of the sockets, both of the "open" and "weatherproof" types, to their supporting bases only by means of screws, rivets or the like. As is well known, said shells are commonly screw threaded to receive the screw threaded bases of the lamps and form one of the lamp terminals, being commonly and preferably made of thin sheet copper and, consequently, very soft. Due to the short engaging surfaces between said attaching screws and shells, it is found in practice that said shells are quite frequently torn by said attaching screws and rendered worthless by the strains to which they are subjected in screwing the lamps into the same.

One object of my invention is to prevent the tearing of said shells in this manner and to this end my invention consists in providing long interlocking surfaces between said shells and their supporting bases, independent of the attaching screws, whereby the strain due to screwing in the lamps will be so distributed that it will not be great enough at a given point to tear said shells.

Further objects of the invention are to provide a "weatherproof" socket, the shell of which may be removed and replaced independently of and without in any way affecting the other parts of the socket, thus providing for quickly and conveniently renewing a socket the shell of which has been stripped or burned out; and, in a "weatherproof" socket, to provide means for inter-

locking the button attached to the shell and which forms the insulating support for the contacts for connecting the lamp terminals with the lead wires, with the supporting base so as to relieve the lead wires from all strain to which they would be subjected by turning of said button relatively to said supporting base and obviating all liability of said lead wires being broken or disconnected from this cause.

To effect the object of the invention, as it relates to providing a socket in which the shell may be removed and replaced independently of and without in any way affecting the other parts of the socket, the button which forms the insulating support for the contacts for connecting the lamp terminals with the lead wires is secured to the outer surface of the rear end of said shell by means accessible inside of said shell and separate from the means for securing said button to the supporting base of the socket.

To effect the objects of the invention, as it relates to means for interlocking the button attached to the shell with the supporting base, said button is provided with a rib or projection on its rear surface, which will be embedded in the cement or wax used for sealing said socket, thus interlocking said button with the supporting base and effectually preventing relative turning of said button and base. Obviously, when said button is secured inside of the shell, it will be necessary to form a suitable hole or opening in the rear end of said shell in order that the rib or projection on said button may project at the rear end of said shell to provide for interlocking the same with the cement or wax used for sealing the socket.

The invention also consists of the various other features, and details of construction hereinafter described and claimed.

In the accompanying drawings, in which my invention is fully illustrated,—Figure 1 is a front view of a "weatherproof" socket 100 of my invention. Fig. 2 is a similar view of the supporting base. Figs. 3 and 4 are sectional views on the lines 3—3 and 4—4, respectively, of Fig. 1; and Fig. 5 is a rear view of the button attached to the rear end 105 of the shell.

Referring now to the drawings, 1 designates the supporting base of a "weatherproof" socket made of porcelain or other suitable insulating material, which is adapt-

ed to be secured in desired position by screws inserted through holes 2 therein and which comprises a tubular portion 3 the bore of which is adapted to receive the shell 4 so as to 5 inclose said shell and protect the same from the weather, all in a familiar manner. The usual interior shoulders 5 on the tubular section 3 of the base define the position of the shell 4 therein and afford a rigid support there- 10 for.

To provide for removing and replacing the shell 4 independently of other parts of the socket, as should said shell become stripped or burned out, the button 6, which is made 15 of suitable insulating material, as porcelain, and which forms an insulating support for the electrical contacts for connecting the lamp terminals with the lead wires 7, instead of being secured inside of said shell, in the 20 manner heretofore common, is attached to the rear end of said shell by suitable means which admit of being readily disengaged, as by screws 8 and 9 the heads of which are exposed within said shell. As shown, the contacts for connecting the lamp terminals with 25 the lead wires 7 consist of an attaching screw, as 8, and a central binding screw 10, the rear or inner end of the shell 4 being cut away, as shown at 11, to prevent said binding screw 10 from contacting with said shell, which would cause a short circuit. To further insure against short circuiting, a boss 12 is formed on the button 6 through which the binding screw 10 passes and which 30 projects a desired distance through the hole or opening 11 in the rear end of said shell.

The button 6, and through it, the shell 4, are adapted to be secured in position within the bore of the tubular portion 3 of the supporting base 1 by means of the lead wires 7, which as shown, extend out through lateral openings 13 in said supporting base, and by the cement or wax 14 used for sealing the socket against the weather, said cement or 45 wax being poured into the cavity in the base 1 through a suitable hole therein, as at 15, and a sufficient quantity of cement or wax being used to entirely fill said cavity, thus rendering the entire structure rigid. With 50 this construction, it is obvious that the button 6 will form, in effect, a part of the supporting base 1 and, the heads of the attaching screws 8 and 9 being exposed at the inside of the shell 4, that, by removing said screws, 55 said shell may be detached and replaced without affecting other parts of the socket.

A particular feature of my improved socket, whether of the "open" or "weather-proof" type, consists in forming shoulders 16 on the button 6, or in the case of an "open" socket, directly on the supporting base, which are adapted to be closely engaged by the edges of a hole or opening in the rear end of the shell 4, as shown, the hole 11 60 through which the contact screw extends.

Said shell will thus be interlocked with its supporting member and held from turning relatively thereto by long engaging surfaces, which will operate to so distribute the strain due to screwing the lamps in and out 70 as to eliminate all danger of the shell being torn either by said shoulders or the attaching screws 8 and 9.

As a further improvement in "weather-proof" sockets, I form a rib 17 on the rear 75 side of the button 6, which will be embedded in the sealing cement or wax 14 when the cavity in the shell is filled, said rib being so arranged that, with said cement or wax, it will operate to interlock said button with 80 the supporting base 1 against relative turning, thus obviating all danger of breaking or disconnecting the lead wires 7 by said button turning in said base. As shown, said rib extends between the attaching screws 8 and 9 85 and the central binding screw 10, thus also operating to effectually insulate them from each other.

I claim:—

1. As a new article of manufacture, a 90 socket for an incandescent electric lamp, comprising an attaching base having a tubular section and a shell secured therein, a button attached to said shell forming an insulating support for the contacts for connecting the lamp terminals with the lead wires, the cavity in said base in the rear of said shell being filled with sealing cement, and a rib on the rear surface of said button adapted to be embedded in the sealing cement or 95 wax and arranged to form therewith means for interlocking said shell with said base to prevent relative turning thereof.

2. As a new article of manufacture, a 105 socket for an incandescent electric lamp, comprising an attaching base having a tubular section and a shell secured therein, a button attached to said shell forming an insulating support for the contacts for connecting the lamp terminals with the lead 110 wires, the cavity in said base in the rear of said shell being filled with sealing cement, and a rib on the rear surface of said button which extends between said contacts for insulating them from each other, adapted to 115 be embedded in the sealing cement or wax and arranged to form therewith means for interlocking said shell with said base to prevent relative turning thereof.

3. As a new article of manufacture, a 120 socket for an incandescent electric lamp, comprising an attaching base having a tubular section and a shell therein, a button attached to said shell forming an insulating support for the contacts for connecting the 125 lamp terminals with the lead wires, said button being provided with a shoulder which interlocks with a corresponding hole in said shell to prevent relative turning thereof, the cavity in said base in the rear 130

of said shell being filled with sealing cement, and a rib on the rear surface of said button adapted to be embedded in the sealing cement or wax and arranged to form there-
5 with means for interlocking said shell with said base to prevent relative turning thereof.

4. As a new article of manufacture, a socket for an incandescent electric lamp, comprising a supporting base, a button,
10 means for securing said button to said base, a shell and independent means for detach-
ably securing said shell to the outer surface

of said button, said means being accessible for manipulation inside of said shell, whereby said shell may be removed and replaced 15 without affecting other parts of the socket.

In testimony, that I claim the foregoing as my invention, I affix my signature in presence of two subscribing witnesses, this 14th day of May, A. D. 1907.

GEORGE B. McBEAN.
